[57] CLAIM

The ornamental design for a glare reduction shield for
attachment to a vehicle mirror or similar article, as
shown.

DESCRIPTION

FIG. 1 is a front elevational view of a glare reduction
shield for attachment to a vehicle mirror or similar
article showing my new design;

FIG. 2 is a right side elevational view thereof;

FIG. 3 is a left side elevational view thereof;

FIG. 4 is a top plan view thereof;

FIG. 5 is a bottom plan view thereof;

FIG. 6 is a rear elevational view thereof;

FIG. 7 is a sectional view thereof taken along line 7—7
in FIG. 6 showing the channel and assembly configura-
tion that is typical around the periphery thereof.
